BLOWER

Original Filed April 15, 1940

UNITED STATES PATENT OFFICE

2,335,437

BLOWER

Thomas J. Morgan, Chicago, and Arthur S. Dearborn, Hinsdale, Ill., assignors to Ampro Corporation, a corporation of Illinois

Original application April 15, 1940, Serial No. 329,784. Divided and this application July 21, 1941, Serial No. 403,370

7 Claims. (Cl. 230—132)

This invention relates to blowers more especially designed for use with cinematographs. This application is a division of copending application Ser. No. 329,784 filed April 15, 1940.

The main objects of this invention are to provide an improved form and construction of a blower particularly suitable for cooling those parts of a cinematograph which are normally subjected to considerable heat emanating from the source of illumination employed in the device, and also from the driving motor; and to provide a blower which will operate with equal efficiency regardless of the direction of rotation of the impeller or fan member.

The other objects and advantages of the invention will be understood by reference to the following specification and the accompanying drawing wherein there is described and shown a blower embodying the selected form of the invention.

In the embodiment as herein shown in the drawing:

Fig. 1 is a transverse cross sectional view of the improved form of blower incorporated in the casing of a cinematograph adjacent to the lamp.

Fig. 2 is a similar sectional view corresponding to Fig. 1 showing the shiftable vane in the opposite position; and

Fig. 3 is a sectional view taken on the line 3—3 of Fig. 1.

In the construction herein shown, the blower housing 50 has mounted therein an impeller or fan member 135 with which two parts are associated a vane 147 automatically shiftable circumferentially of the fan for altering the form and direction of the spiral contour of the air exit passage from the blower. In practice these parts are all designed and formed in accordance with the best principles of turbine fan design.

The blower housing 50 as herein shown is an integral part of that portion of a cinematograph casing 49 which encloses a lamp 109. The circumferential contour of this blower housing 50 is in the form of two scrolls 50.1 and 50.2 of conventional contour which are joined at 50.3. Thus shaped, the housing, coacting with the shiftable vane 147, as will be more clearly hereinafter explained, provides an air exit from the blower at either the upper or lower inner and open side of the housing 50 as indicated by the arrows in Figs. 1 and 2.

The impeller or fan 135 is of conventional turbine type and is mounted on a shaft 136 of a motor 51. A plate 137 provides support for the blades and closes the outer end of the fan mem-

ber. A hub member 138 on the plate 137 provides support for the fan 135 on the shaft 136. The inner end inwardly of the blades is open wherethrough air is drawn axially and then discharged radially into the area between the fan and the housing 50. When the blower is applied to a cinematograph housing, the air is admitted through the cinematograph casing openings 141, 142, and 143, as indicated by the arrows in Fig. 3.

The shiftable vane 147 is in the form of an arcuate member circumferentially arranged with respect to the fan and pivotally supported on an axis eccentric to that of the fan 147 so that in either of its positions the arcuate member complements the curvature of the scrolls 50.1 and 50.2. Thus with the vane in one position, the spiral outlet passage is narrow or restricted at 144 and gradually enlarges toward the outlet 145. With the vane in the reverse position, the spiral outlet passage is narrow or restricted at 155 and gradually enlarges toward the outlet 156.

To effect these results, the vane 147 is carried by radially disposed arms or plugs 148 mounted on a stud shaft 150 which is supported eccentrically of the vane shaft 136. A counterbalance 152 for the vane 147 is secured thereto by means of a third radial arm 151. The proportions of this counterweight 152 are such that it will effectively coact with the air pressure produced by the fan 135 to aid in the automatic shifting of the vane into one or the other of its positions as shown in Figs. 1 and 2, depending upon the direction of rotation of the fan 135.

The ends of the vane are curled at 153 to provide shoulders adapted for abutment against a pin 154 attached to the housing 50 so as to be located in the path of the shoulders. As the vane shifts from one of its positions to the other the shoulders 153 engage the pin 154 and thus limit the movement of the vane.

A blower structure of this character insures an effective air discharge regardless of the direction of rotation of the fan. The reversing of the fan results in an automatic and immediate reversal of the spiral contour for the surrounding air-exit channel occasioned by the shifting of the vane from one to the other of its positions. This maintenance of an effective flow of air regardless of the direction of rotation of the fan is highly important, particularly when the blower is used with cinematographs of the reversible type. In such cases, regardless of the direction of rotation of the film feeding mechanism, the

lamp and other heat-creating means in the cinematograph are continually subjected to a cooling air current.

We claim:

1. A blower comprising a housing, a reversible fan rotatably mounted in said housing, and a vane circumferentially shiftable between opposite positions for alternating the spiral contour of the outlet passage in said housing. 5

2. A blower comprising a housing, a reversible fan rotatably mounted in said housing, and a vane mounted on an axis eccentric of the axis of said blower and circumferentially shiftable between opposite positions for alternating the spiral contour of the outlet passage in said housing. 10

3. A blower comprising a housing, a reversible fan rotatably mounted in said housing, a vane circumferentially shiftable between opposite positions for alternating the spiral contour of the outlet passage in said housing, and coacting shoulders on said vane and housing for limiting the reversible circumferential movement of said vane. 15

4. A blower comprising a housing, a reversible fan rotatably mounted in said housing, a vane circumferentially shiftable between opposite positions for alternating the spiral contour of the outlet passage in said housing, shoulders on the end of said vane, and a pin on said housing extending into the path of said shoulders and adapted to be engaged by one or the other for limiting the circumferential movement of said vane in one or the other of its directions. 20

5. A blower comprising a housing, a reversible fan rotatably mounted in said housing, and a 25

vane in the form of an arcuate member offset from a radial extension so as to be disposed in the plane of rotation of said fan, said radial extension being mounted eccentrically of said fan axis to permit the circumferential shifting of said member between opposite positions for alternating the spiral contour of the outlet passage in said housing.

6. A blower comprising a housing, a reversible fan rotatably mounted in said housing, a vane in the form of an arcuate member offset from a radial extension so as to be disposed in the plane of rotation of said fan, said radial extension being mounted eccentrically of said fan axis to permit the circumferential shifting of said member between opposite positions for alternating the spiral contour of the outlet passage in said housing, and a counterweight carried by said vane extension and coacting with the discharge from said fan for positioning said vane in the one or the other of its positions. 30

7. A blower comprising a housing the circumferential walls of which are formed by the union of two oppositely disposed scrolls, a fan rotatably mounted in said housing, a vane circumferentially positioned in the plane of rotation of said fan and eccentrically mounted relative to the axis thereof, said vane being circumferentially shiftable between opposite positions whereby in one or the other of its positions it forms a continuation of one or the other of said housing scrolls and thereby alternating the spiral contour of the outlet passage of said housing. 35
